COMBINED LAMP BASE AND CABINET

John F. Robichaud, 1026 N. Jackson St.,
Milwaukee, Wis.

Filed May 20, 1963, Ser. No. 74,960

Term of patent 14 years

(Cl. D48—20)

Fig. 1

The opposite sides of the base and cabinet have substantially the same appearance as the sides shown in the figure.

I claim:

The ornamental design for a combined lamp base and cabinet, substantially as shown and described.
